CLAIM

The ornamental design for a portion of a holder for an electronic device, as shown and described.

DESCRIPTION

FIG. 1 is a front view of the design for a portion of a holder for an electronic device;

FIG. 2 is a front perspective view thereof;

FIG. 3 is a rear view thereof;

FIG. 4 is a rear perspective view thereof;

FIG. 5 is right side view thereof;

FIG. 6 is a left side view thereof;

FIG. 7 is a top end view thereof;

FIG. 8 is a bottom end view thereof;

FIG. 9 is a front view thereof, with the circle portion and design portions therein oriented 180 degrees from the position shown in FIG. 1;

FIG. 10 is a rear view thereof, with the circle portion and design portions therein oriented 180 degrees from the position shown in FIG. 1;

FIG. 11 is front perspective view thereof with another holder;

FIG. 12 is a front view thereof with yet another holder, also showing optional dotted patterns;

FIG. 13 is a rear view thereof along with a portion of the holder of FIG. 12;

FIG. 14 is a right side view thereof with the holder of FIG. 12;

FIG. 15 is a left side view thereof with the holder of FIG. 12;

FIG. 16 is a top end view thereof with the holder of FIG. 12;

FIG. 17 is a bottom end view thereof with the holder of FIG. 12;

FIG. 18 is a front view thereof with yet another holder, and also showing optional dotted patterns;

FIG. 19 is a front perspective view thereof with the holder of FIG. 18;

FIG. 20 is a front view of the design for a portion of a holder for yet another electronic device;

FIG. 21 is a front perspective view thereof with the holder of FIG. 20;

FIG. 22 is a rear view thereof with the holder of FIG. 20;

FIG. 23 is a rear perspective view thereof with the holder of FIG. 20;
FIG. 24 is a right side view thereof with the holder of FIG. 20;
FIG. 25 is a left side view thereof with the holder of FIG. 20;
FIG. 26 is a top end view thereof with the holder of FIG. 20;
FIG. 27 is a bottom end view thereof with the holder of FIG. 20;
FIG. 28 is a front view of the design for a portion of a holder for an electronic device;
FIG. 29 is a front perspective view thereof with the holder of FIG. 28;
FIG. 30 is a rear view thereof with the holder of FIG. 28;
FIG. 31 is a rear perspective view thereof with the holder of FIG. 28;
FIG. 32 is a right side view thereof with the holder of FIG. 28;
FIG. 33 is a left side view thereof with the holder of FIG. 28;
FIG. 34 is a top end view thereof with the holder of FIG. 28;

FIG. 35 is a bottom end view thereof with the holder of FIG. 28;
FIG. 36 is a front view of the design for a portion of a holder for yet another electronic device;
FIG. 37 is a front perspective view thereof with the holder of FIG. 36;
FIG. 38 is a rear view thereof with the holder of FIG. 36;
FIG. 39 is a rear perspective view thereof with the holder of FIG. 36;
FIG. 40 is a right side view thereof with the holder of FIG. 36;
FIG. 41 is a left side view thereof with the holder of FIG. 36;
FIG. 42 is a top end view thereof with the holder of FIG. 36;
and,
FIG. 43 is a bottom end view thereof with the holder of FIG. 36.
The broken lines shown in the drawings are for illustrative purposes only and form no part of the claimed design.
